JAMES McKECHNIE, OF BARROW-IN-FURNESS, ENGLAND, ASSIGNOR TO VICKERS
LIMITED, OF BARROW-IN-FURNESS, ENGLAND.

INJECTION OF LIQUID FUEL IN INTERNAL-COMBUSTION ENGINES.

1,193,909.

Specification of Letters Patent. Patented Aug. 8, 1916.

Application filed August 5, 1913. Serial No. 783,054.

To all whom it may concern:

Be it known that I, JAMES McKECHNIE, a subject of the King of Great Britain, residing at Naval Construction Works, Barrow-in-Furness, in the county of Lancaster, England, have invented certain new and useful Improvements in the Injection of Liquid Fuel in Internal-Combustion Engines, of which the following is a specification.

This invention relates to the injection of liquid fuel at extremely high pressures into the cylinders of internal combustion engines of the type in which the fuel is ignited as it enters the cylinders, the chief object of the invention being to insure the injection of such fuel unmixed with air at a pressure which is the same for varying fuel supply and engine power, so that a greater range of power and increased economy at low powers may be obtained.

According to my invention the fuel is injected by the direct action of a pump the plunger of which has a stroke capable of pumping a large excess of fuel and the high pressure desired at the period of injection is attained gradually during the idle portion of the pump compression stroke, by exercising an increasing choking action on the escape of the excess fuel, which choking action is conveniently produced by mechanically operating the suction valve so that it closes slowly during the first part of the said compression stroke. The fuel pressure is by this means steadily raised while the valve is slowly closing, the final portion of the pump stroke, with the valve closed, being arranged to give a fuel charge only slightly in excess of the full charge required. The gradual increase of pressure up to the maximum avoids any sudden shock which would otherwise be experienced in delivering the fuel at the high pressures necessary and in the short time allowed. The charge is determined by the operation of an injection valve, which I prefer to fit in the pump casing but which may be fitted to the engine cylinder. The opening of this valve, which is timed to occur during the final portion of the pump stroke, is controlled by any suitable mechanism such as a cam and lever, and the period and extent of valve opening regulate the charge of fuel injected. The excess of fuel delivered by the pump is returned to the suction side through a relief

valve which determines the maximum pressure of injection and as there is always some excess to be passed through the relief valve the pressure is the same for the injection of both large and small quantities of fuel. The opening of the injection valve may be regulated by a sliding cam having a tapering cam surface of suitable form, so that an axial movement of the cam simultaneously adjusts the timing and the period and extent of opening. Or I may effect the desired adjustment through the cam operated valve lever by providing, for example, a movable fulcrum for a jointed lever, the extent of valve opening varying according to the position of the fulcrum. The timing of the valve may be simultaneously adjusted by mounting the movable fulcrum on an eccentric or a swinging arm or other suitable device which causes the cam roller to advance to or recede from the cam as the leverage is altered by the movement of the fulcrum. All the cylinders of a multi-cylinder engine may be controlled simultaneously by hand operated gear acting through the cam or cam lever mechanism on the injection valves in the manner above described.

In order that the said invention may be clearly understood and readily carried into effect the same will be described more fully with reference to the accompanying drawings, in which:—

Figure 1 is a section of pump and valve apparatus embodying the principles of my invention. Fig. 2 is a side elevation of the suction valve cam. Fig. 3 is a diagram illustrating the application of the invention to a multi-cylinder engine.

A is the pump body or casing, which in the construction illustrated in Fig. 1 carries all the valves required for the present method of injection.

B is the pump plunger.

C is the pump suction valve operated by the cam *c* on the cam shaft D. 100

E is the relief valve.

F is the injection valve controlled by the sliding cam *f* on the shaft D.

H is a nozzle in the cylinder cover *J*, through which nozzle the oil is injected into the cylinder. 105

K is a pressure gage on the small bore pipe *h* connecting the nozzle H to the pump casing.

The pump plunger B is driven by the ec- 110

centric b on the shaft D, the diameter of the plunger and its stroke being so proportioned that the volume swept out by the plunger is in excess of the maximum amount of fuel required for each stroke. The plunger extends through the gland b' in the casing A and its head b^2 slides in an extension a of the casing and forms a ball and socket joint with the end of a short rod b^3 on the eccentric b' . During the suction stroke of the plunger B the fuel is drawn into the passage a' of the pump casing from the fuel chamber L, which is kept supplied with fuel through the pipe l , the suction valve C being opened against the pressure of the spring c' . Above the short stem of the suction valve is a valve operating rod c^2 passing through the gland c^3 and provided with a head c^4 connected to the rod c^2 at c^5 sliding in an extension a^2 of the pump casing and having a spring c^5 bearing on its under side. The cam c acts on the rod c^2 against the spring c^5 through the roller c^6 on the head c^4 . The cam therefore may maintain the suction valve C open after the suction stroke has ended and the compression begun. The cam c is so formed as to allow the valve C to close gradually during the compression stroke so that the fuel pressure in the passage a' due to the compression stroke of the plunger B gradually increases by reason of the choking action and reaches its maximum only at or after the complete closing of the suction valve. The valve C is held fully open while the concentric cam face c^7 (Fig. 2) is operative, but when the cam c has turned until a point at about c^8 on the sloping face c^9 at the end of the part c^7 is reached, the pump begins its delivery stroke. Immediately after, the very gradual cam slope c^{10} becomes operative to permit the valve C to slowly close, and thus produce a choking action upon the fuel. This choking action continues at increasing strength until the point c^{11} is reached at which complete closing of the valve C takes place and full fuel pressure is exerted. The valve C remains closed throughout the remainder of the delivery stroke corresponding to the concentric part c^{12} of the cam c .

The maximum pressure developed by the pump is determined by the relief valve E on which bears the powerful spring e , the strength of which spring can be regulated by screwing the separate valve head e' in or out of the plug a^3 secured in the valve body A, this plug having a relief opening e^2 in its side through which excess fuel can escape to a reservoir or back to the chamber L. The spring e is set so as to give the maximum pressure desired, this pressure being attained before the plunger B reaches the end of its stroke. The remainder of the stroke forces the fuel into the cylinder on the opening of the valve F and drives the excess fuel

(usually a small portion only) through the relief valve. The maximum pressure may thus be practically maintained throughout the injection, owing to the excess supply from the pump during the latter part of its stroke.

The injection valve F is shown in Fig. 1 fitted to the pump body, but it may of course be situated in any convenient position between the pump and the nozzle H. The cam f opens this valve at the required point of the engine stroke through an arm f' on a bracket a^4 , this arm bearing on a collar f^2 on the valve stem f^3 , the upper end of which is acted upon by the spring f^4 placed in a cup at the end of a bracket a^5 , the spring f^4 closing the valve when released by the arm f' . The timing cam f is arranged to slide upon the cam shaft D, a groove f^5 receiving the cam adjusting means. The cam surface varies from one end of the cam to the other so that the points of opening and closing of the valve F can be regulated in accordance with the running of the engine and the power to be developed. The opening of the valve F always occurs after the closing of the pump suction valve and when the maximum fuel pressure has been attained so that immediately the valve F is opened the fuel is forced under the extremely high pressure given by the pump and relief valve through the small bore pipe h and the cylinder nozzle H, the fuel entering the cylinder as a fine spray which instantly vaporizes.

The general operation of the fuel injection mechanism is as follows:—The pump plunger B is driven from the engine through the shaft D and eccentric b , the stroke of the pump being constant. The suction valve C is also controlled by the same shaft D through the cam c which is so formed as to permit the suction valve to close very gradually. At each revolution, therefore, of the shaft D the pump B on its upward stroke draws in a constant volume of fluid from the fuel chamber L through the suction valve C. On the return or compression stroke of the plunger the suction valve C does not close immediately as would be the case if it were not under mechanical control. The cam c allows it to approach its seat gradually the passage being reduced sufficiently to exercise a choking effect so that the pressure of the fuel in the passage a' gradually rises. At a convenient point in the pump stroke the valve C is allowed to close completely and the pump works in its normal manner. The maximum pressure of the fuel is however limited by the spring controlled relief valve E. After the closing of the suction valve the injection valve F is opened by the cam f , the time and period of opening being variable as already described. The pump plunger continues its compression stroke while the injection valve

is open so that it directly forces the fuel under extremely high pressure through the valve and into the cylinder.

As applied to a multi-cylinder engine, the arrangement illustrated diagrammatically in Fig. 3 may be used, in which the fuel under pressure passes into a main supply pipe h' from which it is supplied to the injection valves F' , one for each cylinder J' , these valves being situated outside the pump body A . They are operated from the sliding cams f on the cam shaft D in the manner already described. The small bore tubes h lead from these valves to injection nozzles in each of the cylinder heads J . The relief valve E' is also shown outside the pump body and the excess fuel flows back into the pump through the small pipe e^3 .

What I claim and desire to secure by Letters Patent of the United States is:—

1. Fuel injecting apparatus for internal combustion engines, comprising a pump adapted to pump a large excess of fuel at each stroke, mechanically operated valve mechanism for regulating the supply of fuel to the engine cylinder and for admitting it only during the latter part of the pump compression stroke, a valve allowing escape of fuel during the idle portion of the pump compression stroke and mechanical means for maintaining the opening of the said valve, before the admission of the fuel to the cylinder, so small as to exercise a substantial choking effect on the escape of the fuel and for slowly closing the valve so as to increase the choking effect up to complete closing and thus gradually to raise the fuel pressure up to the high pressure of injection.

2. Fuel injecting apparatus for internal combustion engines, comprising a pump adapted to pump a large excess of fuel at

each stroke, mechanically operated valve mechanism for regulating the supply of fuel to the engine cylinder and for admitting it only during the latter part of the pump compression stroke, a pump suction valve and means for maintaining the opening of the said suction valve during the idle portion of the compression stroke of the pump so small as to exercise a choking effect on the escape of the fuel, and for slowly closing the valve so as to increase the choking effect up to complete closing and thus gradually to raise the fuel pressure up to the high pressure of injection.

3. Fuel injecting apparatus for internal combustion engines, comprising a pump adapted to pump a large excess of fuel at each stroke, mechanically operated valve mechanism for regulating the supply of fuel to the engine cylinder and for admitting it only during the latter part of the pump compression stroke, a valve allowing escape of fuel during the idle portion of the pump compression stroke, mechanical means for maintaining the opening of the said valve, before the admission of the fuel to the cylinder, so small as to exercise a substantial choking effect on the escape of the fuel and for slowly closing the valve so as to increase the choking effect up to complete closing and thus gradually to raise the fuel pressure up to the high pressure of injection, and a relief valve between the pump and the engine, set to open at a predetermined fuel pressure which controls the pressure of injection.

In testimony whereof I affix my signature in presence of two witnesses.

JAMES McKECHNIE.
